(57) **CLAIM**

The ornamental design for a female portable urinal as shown and described.

DESCRIPTION

FIG. 1 is a perspective view of a female portable urinal showing our new design;

FIG. 2 is a front, bottom perspective view thereof;

FIG. 3 is a top, rear perspective view thereof;

FIG. 4 is a front elevational view thereof;

FIG. 5 is a left side elevational view of the female portable urinal thereof, the right side being a mirror image thereof; and,

FIG. 6 is a rear elevational view thereof.

The broken lines illustrate portions of the female portable urinal that form no part of the claimed design.

1 Claim, 6 Drawing Sheets
